(57) **CLAIM**

The ornamental design for the piece of jewelry, as shown and described.

DESCRIPTION

FIG. 1 is a front, right side perspective view of an embodiment of a piece of jewelry;

FIG. 2 is a front view thereof;

FIG. 3 is a right side view thereof;

FIG. 4 is a left side view thereof;

FIG. 5 is a top plan view thereof;

FIG. 6 is a bottom plan view thereof;

FIG. 7 is a front view of the piece of jewelry shown with alternate unclaimed environmental structure; and,

FIG. 8 is a front view of the piece of jewelry shown with a second alternate unclaimed environmental structure.

Elements shown in phantom illustrate environment and form no part of the claimed design.
